UNITED STATES PATENT OFFICE.

GUY V. WILLITS, OF INDIANAPOLIS, INDIANA.

ROTARY FAN.

Application filed July 12, 1927. Serial No. 205,182.

This invention relates to rotary fan construction, and the prime feature of the invention is the provision of means for tilting the fan to any desired working angle, either 5 upwardly or downwardly, and at the same time varying the blowing direction in a horizontal angle, without changing the vertical angle of the fan breeze.

A further feature of the invention is the 10 provision of means for causing the fan to revolve in a gyroscopic path around its supporting base, the fan traveling in a set path at all times.

A further feature of the invention is the 15 provision of means for causing the fan and its controlling motor to rotate in a circular path, while the supporting base remains stationary.

A further feature of the invention is the 20 provision of means for securely locking the fan and its associated parts in fixed adjusted position.

A further feature of the invention is the 25 provision of a flexible means for holding parts of the fan structure against rotation, and at the same time permitting said parts to be tilted to any desired angle.

A further feature of the invention is the 30 provision of means for conducting an electrical current from the stationary part of the fan structure to the rotating part thereof, and in such manner that the current will be fed to the motor of the fan at all times, during the operation of the apparatus.

35 Other objects and advantages will be hereinafter more fully set forth and pointed out in the accompanying specification.

In the accompanying drawings which are made a part of this application, Figure 1 is 40 a side elevation of a fan structure showing in both full and dotted lines, the line of travel of the fan as it travels on its base; Fig. 2 is a detail sectional view of the upper end of the fan base with its component 45 parts; Fig. 3 is an elevation, showing in section, part of the tiltable non-rotatable portion of the fan structure; Fig. 4 is a sectional view thru the rotating part of the fan structure; and Fig. 5 is a detail elevation 50 of the flexible member for holding the non-rotatable part against rotation.

Referring to the drawings in which similar reference numerals designate corresponding parts thruout the several views, 1 55 indicates the base of the fan structure, which

may be constructed in the conventional or other preferred form, the upper end of the base terminating in a socket 2, in which is swivelly mounted a stem 3 of a bifurcated head 4, the stem 3 being normally retained 60 within the socket 2, by means of a set screw 5.

Between the paralleling arms 6 of the head 4 is a shank 7 of a bearing 8, the shank 7 being pivoted between said arms 6 by a 65 pivot pin 9, said pin passing thru one of said arms and the shank 7 and threading into the other arm, so that said arms may be squeezed against the shank to aid in holding said shank in adjusted position. Said 70 shank is positively locked in adjusted position by means of a set screw 10, which threads thru one of the arms 6 and against one face of said shank.

Extending upwardly from the bearing 8 75 is a pivot pin 11, on which is loosely mounted a gear wheel 12, to the under face of which is attached a block 13 of insulating material, thru which are extended posts 14 and 15, carrying at their upper ends brushes 80 16 and 17, respectively, said posts being connected to current carrying wires 18, which in turn connect with the conventional switch 19. As the gear wheel 12 is loosely mounted on the pin 11, means is provided for preventing rotation of the wheel and at the same time permitting the same to be tilted to any desired angle, comprising a bar 20, preferably round in cross section, the upper end 85 of which is pivoted between ears 21 on the under face of the block 13, said bar 20 extending thru an eye 22 of an arm 23, fixed to the base 1. By arranging the bar 20 in such flexible manner, the bearing 8 and gear wheel 12 may be tilted to different angles, as 90 indicated by full and dotted lines in Fig. 1, and at the same time holding said gear wheel 95 against rotation.

Mounted on the pin 11, above the gear wheel 12, is a block 24 of insulating material, 100 on which are mounted induction rings 25 and 26, which cooperate respectively, with the brushes 16 and 17, said rings being preferably in stepped relation with each other. Connected with the rings 25 and 26 105 are posts 27 and 28, respectively, to which are attached induction wires 29 and by means of which the current is conveyed to the motor within the housing 30, said motor 110 being employed for driving the conventional

form of fan 31. The insulating block 24 and the housing 30 are fixed to the pin 11 by means of a set screw 32, so that they will rotate therewith. The lower portion of the stem 3 has a pair of collars 33 thereon, between which the end of the set screw 5 passes, thus holding the stem against longitudinal movement, but permitting the stem to freely rotate.

10 The fan 31 is caused to travel in a circular path around the base 1 by providing a cog 34, which meshes with the gear wheel 12, the cog 34 being mounted on a shaft 35 extending downwardly in a bearing 36 on the 15 housing 37 encasing the fan shaft 38. The shaft 35 is driven in the conventional manner from the shaft 38, and as the cog is in mesh with the non-rotating gear 12, the fan will be caused to travel in a circular path 20 about the base 1, and as the cog 34 moves around the periphery of the gear 12, said gear will rock or incline with the ever changing position of the bearing 8, thus 25 always maintaining the teeth of the gear 12 in position to mesh with the teeth of the cog 34.

To compensate for any variance of travel between the gear wheel 12 and the cog 34, said cog is loosely mounted on the shaft 35, 30 and is normally held in fixed relation with the shaft by means of a spring 39, the tension of which forces the hub of the cog against a shoulder 40 on the shaft 35 with sufficient 35 force to cause the cog to normally rotate with the shaft. In the event that the movements of the mechanism are inadvertently or otherwise obstructed, the cog 34 will slip on its shaft, automatically preventing operation of the gears against destructive over- 40 loads. The tension of the spring 39 may be regulated by adjusting the nut 41 along on the lower end of the shaft 35, which is threaded for that purpose.

45 By providing the bar 20 and eye 22 and conducting the electrical energy from its source of supply to the fan motor in the manner shown, the fan structure is very greatly simplified over former fan structures of this class, thus not only greatly reducing the cost of production, but reducing the 50 wearing parts to a minimum without jeopardizing the strength and durability of the device.

55 As previously stated, the fan may be tilted in a vertical direction, to any desired angle above or below the horizontal, by first releasing the set screw 10 and loosening the pivot pin 9, the shank 7 of the bearing 8 pivoting on the pin 9 with the lower end 60 thereof swinging laterally between the arms 6. After the fan has been tilted to the proper angle the pin 9 and set screw 10 are again tightened for holding the fan firmly in its adjusted position.

65 From the foregoing, it will be understood

that the gear 12 does not rotate, but that it weaves about in a path determinable by a succession of gyrated positions.

The relative direction of rotation of the fan 31 and the motor 30 is such that the 70 resulting gyroscopic force of same tends to rotate the fan mechanism as a whole, harmoniously with the gears 12 and 34, in respect to the socket 2.

While the description and drawing illustrate in a general way, certain instrumentalities which may be employed in carrying the invention into effect, it is evident that many modifications may be made in the various details, without departing from the 80 scope of the appended claims, it being understood that the invention is not restricted to the particular forms, herein described.

I claim as my invention:

1. In a fan structure, a base having a 85 socket at its upper end; a stem swivelly mounted in said socket; a bifurcated head attached to said stem; a bearing; a shank on the bearing adapted to enter between said bifurcated parts of the head; means for 90 locking said shank against movement between said bifurcated portions; a fan motor carried by said bearing; a fan operated by said motor; means for conveying electrical energy to said motor from a stationary to a 95 movable element; and means for causing said motor to travel in a circular path around its base.

2. In a fan structure, a base having a 100 socket in its upper end; a stem swivelly mounted in said socket; a bifurcated head on said stem; a bearing pivotally attached to said head; means for locking said bearing to said head; a gear wheel loosely mounted on said bearing; means for forming a flexible connection between said gear and said base; whereby said gear will be held against rotation and have weaving action; a fan structure fixed to said bearing; and means 105 operated by the fan structure for causing it to rotate around said base.

3. In a fan structure, a base; a head swivelled to said base; a bearing adjustably attached to said head and adapted to rotate therewith; a motor fixed to said bearing; a fan connected to said motor and operable thereby; a gear mounted on said bearing; means for flexibly connecting the gear with said base for holding the gear against rotation and permitting said gear to weave gyroscopically as the bearing rotates; and a cog operated by said fan structure and meshing with said gear for causing said fan to travel laterally in a circular path around said base. 115

4. In a fan structure, a base; a head swivelly connected with said base; a bearing pivoted to said head and adapted to swing laterally; means for locking said bearing in its 120 adjusted position; a gear wheel loosely mounted on said bearing; a yielding con- 125

nection between said gear wheel and said base, whereby said gear may successively tilt while being held against rotation on the bearing; a fan proper; a motor for operating said fan; means for fixing said motor to said bearing; and a cog operated by said fan member and meshing with said gear for causing the fan to revolve around said base, when the fan is rotated.

5 5. In a fan structure, a base; a head swivelled to said base; a bearing adjustably attached to said head and adapted to rotate therewith; a motor fixed to said bearing; a fan connection to said motor and operatable thereby; a gear mounted on said bearing; means for flexibly connecting the gear with said base for holding the gear against rotation and permitting said gear to weave as the bearing rotates; a cog operated by said 10 fan structure and meshing with said gear for causing said fan to travel laterally in a circular path around said base; and yielding means for normally holding said cog in fixed relation with its operating parts.

15 6. In a fan structure, a stationary base; a head rotatably attached to said base; a bearing adjustably attached to said head and rotatable therewith; a non-rotatable gear wheel loosely mounted on said bearing; and means for conveying an electric current from 20 the stationary base to said rotating parts and thru said gear wheel.

7. In a fan structure, a stationary base; a head rotatably attached to said base; a bearing adjustably attached to said head and 25 rotatable therewith; a non-rotatable gear mounted on said bearing; a pair of current conveying brushes carried by said gear wheel; and a pair of induction rings carried by and rotatable with said bearing with 30 which said brushes cooperate, whereby an electric current may be conveyed from a stationary element to a rotating element without interruption to the current.

8. In a fan structure, a base; a head swiv- 45 elled to said base; a bearing adjustably attached to said head and adapted to rotate therewith; a motor fixed to said bearing; a fan connected to said motor and operatable thereby; a gear mounted on said bearing; 50 means for flexibly connecting the gear with said base for holding the gear against rotation; and permitting said gear to weave as the bearing rotates; and a cog operated by said fan structure and meshing with said 55 gear for causing said fan to travel laterally in a circular path around said base, in a direction harmonious with the gyroscopic force caused by rotation of said fan.

In testimony whereof, I have hereunto set 60 my hand on this the 6th day of July, 1927,
A. D.

GUY V. WILLITS.
